US00D441659S

(12) **United States Design Patent**
Di Canio et al.

(10) Patent No.: **US D441,659 S**
(45) Date of Patent: **** May 8, 2001**

(54) **BOTTLE**

(75) Inventors: **Robert G. Di Canio**, Naperville, IL (US); **Suppayan M. Krishnakumar**, Nashua, NH (US); **Jeff Lichtman**, Evanston; **Jeffrey L. Pattee**, Palatine, both of IL (US); **David P. Piccioli**, Auburn, NH (US); **Christopher D. Rowe**, Barrington; **Tia-Maria Smith**, Chicago, both of IL (US)

(73) Assignee: **Stokely-Van Camp, Inc.**, Chicago, IL (US)

(*) Notice: This patent is subject to a terminal disclaimer.

(**) Term: **14 Years**

(21) Appl. No.: **29/085,978**

(22) Filed: **Apr. 2, 1998**

Related U.S. Application Data

(63) Continuation-in-part of application No. 29/078,570, filed on Oct. 28, 1997.

(51) LOC (7) Cl. **09-01**

(52) U.S. Cl. **D9/550**

(58) Field of Search D9/520, 537, 540, D9/550, 551, 553; 215/381, 383, 384

(57) CLAIM

We claim the ornamental design for bottle, as shown.

DESCRIPTION

FIG. 1 is a perspective view of a bottle showing our new design;

FIG. 2 is a front view of the bottle depicted in FIG. 1, the opposite side being identical;

FIG. 3 is a side view of the bottle depicted in FIG. 2, representing a ninety degree rotation of the bottle about its vertical center axis from the front view depicted in FIG. 2, the opposite side being identical;

FIG. 4 is a top view of the bottle depicted in FIG. 2; and,

FIG. 5 is a bottom view of the bottle depicted in FIG. 2.
